UNITED STATES PATENT OFFICE

HERMAN DEUTSCHMEISTER, OF NEW YORK, N. Y.

COMBINATION PAMPHLET HOLDER AND SAMPLE CARRIER

Application filed December 27, 1926. Serial No. 157,165.

This invention relates to advertising devices and more particularly is directed to a combination pamphlet holder and sample carrier.

5 One object of the invention is to provide a device of the character described in the form of an improved wrapper for advertising matter, portions of which are constructed to engage with a box, receptacle or package 10 containing a sample to which the advertising matter refers.

Another object of the invention is to provide a device of the character described including a folder type of wrapper having a flap closure for retaining printed matter, a portion of said wrapper being slotted to form tabs for engaging a receptacle to attach the latter to the wrapper and for holding the flap closure shut.

20 A further object of the invention is to provide a device of the character described, which shall be very simple and easy to construct yet form a neat and attractive article, cheap to manufacture, and practical and efficient to a high degree in use.

Other objects of this invention will in part be obvious and in part hereinafter pointed out.

The invention accordingly consists in the 30 features of construction, combinations of elements, and arrangement of parts which will be exemplified in the construction herein-after described, and of which the scope of application will be indicated in the following claims.

In the accompanying drawings, in which is shown one of the various possible illustrative embodiments of this invention,

Fig. 1 is a perspective view of the improved advertising holder and sample carrier embodying the invention.

Fig. 2 is a cross-sectional view taken on line 2-2 in Fig. 1.

Fig. 3 is a fragmentary perspective view showing a modified form of carton attachment means embodying the invention.

Fig. 4 is a perspective view showing a modified construction of the advertising holder and sample carrier embodying the invention.

Referring in detail to the drawing, 10 denotes an advertising holder and sample carrier embodying the invention which is here seen to comprise a cover or wrapper 11 formed of any suitable sheet material, such as cardboard, heavy or light stock paper or the like. Said wrapper may be formed of a single sheet blank comprising a central portion 11a and foldable flaps 11b extending longitudinally from opposite sides of said central portion 11a, said flaps being slotted as at 11c to form tabs 12 which are adapted to engage a receptacle or package 13 in a manner hereinafter more fully described. The sheet forming said wrapper 11 is cut to form the blank, creased and folded to form an enveloping member for enclosing printed matter 14, such as directions for use, testimonials, advertising items, etc., as is clearly shown in Fig. 1. The device 10 is particularly adapted to accompany samples forming the contents of said receptacle 13 and as here shown the latter comprises a box having a casing 13a which forms a housing for a slidable compartment 13b, as is shown in Fig. 2. The tabs 12 are formed for insertion in the casing 13a between the bottom side thereon and said compartment member 13b, (see Fig. 1), so that the receptacle 13 is secured to the device 10 to overlie the flaps 11b and retain the latter in their folded position.

One or more suitably shaped openings 11d may be provided in said flaps 11b for exposing a portion of the printing on the matter 14 enclosed in the wrapper 11, as is clearly shown in Fig. 1.

The practical use of the device 10 is now apparent. The printed matter 14 is enclosed in the folded wrapper 11 and the receptacle 13 containing the sample of the product to be distributed is attached to the wrapper by inserting the tabs 12 into the ends of the receptacle casing 13a between a wall of said casing and the compartment member 13b. The receptacle thus retains the device in assembled form and it may be distributed in any desired manner as by enclosing it in an envelope and mailing.

Although the construction of the combination

tion pamphlet holder and sample carrier 11 is shown in Figs. 1 and 2 as having two tabs 12, it is to be understood that but a single tab may be used for many purposes.

5 In Fig. 3 a modified form of tab construction is shown. Here, the wrapper 111 is provided with a central body portion 111a and foldable side flaps 111b and the aligned end edges 111c of said flaps are slotted as at 111d to form tabs 112 which are adapted to be inserted between and engaged with portions of the receptacle (not shown) in a manner similar to that shown in Fig. 1.

15 In Fig. 4 a modified construction of the advertising holder and sample carrier embodying the invention is shown. Here the wrapper is made in the form of an envelope 211 having a closed end 211a, the edge portion 211b of the open end of said wrapper being slotted as at 211c to form tabs 212. Said tabs are adapted to be inserted between and engaged with portions of the receptacle (not shown) in the manner described above for wrapper 11 and 111. The wrapper 211 may also be 20 provided with a suitably shaped central opening 211d for exposing a portion of the printing on the matter enclosed in the wrapper, as is clearly shown in Fig. 4.

It will thus be seen that there is provided 30 a device in which the several objects of this invention are achieved and which is well adapted to meet the conditions of practical use.

As various possible embodiments might be 35 made of the above invention, and as various changes might be made in the embodiment above set forth, it is to be understood that all matter herein set forth or shown in the accompanying drawing is to be interpreted as 40 illustrative and not in a limiting sense.

Having thus described my invention, I claim as new and desire to secure by Letters Patent:

1. A device of the character described 45 formed of sheet material comprising a central portion and foldable flaps extending longitudinally from opposite sides of said portion forming a wrapper adapted to enclose printed matter, each of said flaps having a slotted portion, said slotted portions forming cooperating means adapted to secure a receptacle to overlie the flaps and retain said flaps in folded position.

2. In a device of the character described, in 55 combination, a wrapper formed of sheet material comprising a central portion and foldable flaps extending longitudinally from opposite sides of said portion, edge portions of said flaps being slotted, a receptacle attached 60 to said slotted portions to retain said flaps in folded position.

3. In combination, a device formed of a 65 single piece of sheet material cut, creased and folded to have a body portion, foldable flaps extending longitudinally from opposite sides

of said portion forming a wrapper adapted to enclose printed matter, and integral means incorporated in the edge portions of each flap forming an attachment member and a package secured to said attachment member to overlie the flaps and to retain said flaps folded.

4. In combination, a device of the character described formed of a single piece of sheet material cut, creased and folded to have a body portion, foldable flaps extending longitudinally from opposite sides of said portion forming a wrapper adapted to enclose printed matter, said flaps having tabs, and a receptacle engaging said tabs to overlie said flaps and retain the same in folded position.

5. In combination, a device of the character described formed of a single piece of sheet material cut, creased and folded to have a body portion, and foldable flaps extending longitudinally from opposite sides of said portion forming a wrapper adapted to enclose printed matter, the aligned edges at one end of said flaps being slotted to form attachment means, and a receptacle attached to said means to overlie the flaps and to retain said flaps folded.

In testimony whereof I affix my signature.

HERMAN DEUTSCHMEISTER.
